UNITED STATES PATENT OFFICE.

LEWIS CHESSER, OF WILSON, WASHINGTON.

SOIL-PULVERIZER.

1,089,325.

Specification of Letters Patent.

Patented Mar. 3, 1914.

Application filed September 3, 1913. Serial No. 787,974.

To all whom it may concern:

Be it known that I, LEWIS CHESSER, a citizen of the United States, residing at Wilson, in the county of Lewis and State of Washington, have invented new and useful Improvements in Soil-Pulverizers, of which the following is a specification.

This invention relates to soil pulverizers, and it has for its object to produce a machine of this class embodying a revolvably supported pulverizing cylinder which shall be simple in construction and effective in operation.

A further object of the invention is to produce a machine of the class described having simple and efficient means for raising the cylinder to an inoperative position for transportation and when not in active use.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a top plan view of a machine constructed in accordance with the invention. Fig. 2 is a rear elevation of the same. Fig. 3 is a longitudinal sectional view taken on the line 3—3 in Fig. 1, the cylinder being shown in earth engaging position. Fig. 4 is a view similar to Fig. 3, but showing the cylinder in raised position. Fig. 5 is a sectional detail view taken through the counter shaft and its bearing on the line 5—5 in Fig. 1. Fig. 6 is a perspective detail view of a portion of the axle, one of the supporting arms and related parts.

An axle 15 is provided with ground wheels 16 mounted thereon for rotation and with a forwardly extending tongue 17, the front end of which is preferably supported on a tongue truck 18 for the attachment of the draft animals. The tongue is connected 55 with the axle by means of arcuate braces

19 which are extended rearwardly of the axle to form brackets 20.

Each of the brackets 20 is provided at a distance from its rearward extremity with lugs 21 with which rearward extending arms 22 are hingedly connected, said arms being supported on the brackets 20, whereby the downward movement of said arms is limited. The arms 22 are curved downwardly, and they serve to support a cylinder 23 which is equipped with earth-engaging teeth 24. The cylinder may consist of a skeleton structure, and the teeth may be provided with threaded shanks 25 extending through apertures in said skeleton structure and having nuts 26 to enable said teeth to be readily applied, detached and renewed when occasion shall require. The teeth may be made of any desired shape, but they are preferably made triangular in cross section 75 and provided with relatively sharp earth engaging cutting edges.

Rising from the axle adjacent to the ends thereof are uprights 27, said uprights being reinforced by braces 28, the lower ends of 80 which are connected with the braces 19. The uprights 27 support a tubular casing 29 that affords a bearing for a shaft 30. The shaft 30 has at one end a sprocket wheel 31 which is connected by a chain 32 85 with a sprocket wheel 33 associated with one of the ground wheels from which motion will thus be transmitted to the shaft. The latter is provided at its other end with a sprocket wheel 34 which is connected by 90 a chain 35 with a sprocket wheel 36 associated with the cylinder 23 to which rotary motion will thus be transmitted.

The arms 22 that support the pulverizing cylinder are provided at their forward ends 95 with segment racks 37 which are positioned adjacent to the side faces of the brackets 20 and which are engaged by worms 38 formed on shafts 39 supported for rotation in brackets 40 associated with the uprights 27, 100 said shafts being provided at their upper ends with hand wheels 41 whereby they may be conveniently rotated.

The brackets 20 are so positioned in the path of the arms 22 as to support said arms 105 when the cylinder carried thereby is in earth engaging position, the weight of the cylinder being thus to a large extent supported when the machine is in operation. By manipulating the hand wheels 41, the 110

2
arms 22 may be rocked, thereby lifting or elevating the cylinder to a non-engaging position with respect to the ground for convenience in transporting the machine from 5 one place to another.

In operation, motion is transmitted from one of the ground wheels to the counter shaft 30 and from the latter to the pulverizing cylinder. The sleeve 29 which affords 10 a bearing for the shaft 30 is preferably provided with anti-friction bearings, as indicated in Fig. 5, at 42. A seat 43 for the driver or operator is mounted on the tongue 15 sufficiently in advance of the latter to enable the weight of the operator to be utilized in counterbalancing the weight of 17 the pulverizing cylinder.

Having thus described the invention, what is claimed as new, is:—

- 20 1. In a machine of the class described, an axle having ground wheels, brackets extending rearwardly from the axle, cylinder carrying arms hinged upon and supported by the brackets, rack segments at the front 25 ends of the arms, said segments being positioned adjacent to the side faces of the

brackets, and worms engaging the rack segments, the brackets being extended rearwardly in the path of the cylinder carrying arms to limit the downward movement 30 thereof.

2. In a machine of the class described, an axle having ground wheels, hingedly supported arms carrying a revoluble pulverizing cylinder and having rack segments 35 at their forward ends, uprights rising from the axle, a bearing sleeve supported on the uprights, a counter shaft supported for rotation in the sleeve, means for transmitting motion from one of the ground wheels to 40 the counter shaft and from the latter to the cylinder, bearings on the uprights, and shafts supported in said bearings and having worms engaging the rack segments, said worm carrying shafts being provided with 45 hand wheels.

In testimony whereof I affix my signature in presence of two witnesses.

LEWIS CHESSER.
